UNITED STATES PATENT OFFICE

JOHN HERBERT HAMILTON, OF HOLYOKE, MASSACHUSETTS

GUIDING APPARATUS FOR WEBS

Application filed November 10, 1928. Serial No. 318,499.

This invention relates to improvements in apparatus for guiding webs of material such as webs of cloth fabric and the like.

In the manufacture of cloth it is common 5 practise to feed cloth in its flat web form to various machines which operate on the cloth for certain purposes. It is necessary that the web being handled be held in a flat smooth condition and that its side edges be guided 10 laterally of the direction of travel of the web so that the web enters the machine in proper alignment.

According to the principal object of this 15 invention I provide an apparatus for guiding material in web form which is adapted to engage side edges of a traveling web for moving said web laterally of its direction of movement and thereby guiding it. This is accomplished according to the novel features of the 20 invention by the novel combination and arrangement of parts to be hereinafter described and illustrated in the form at present preferred by means of the accompanying drawings.

25 In the drawings

Fig. 1 is an elevational view of a web of material showing a guide of the invention at one side edge thereof.

Fig. 2 is an enlarged plan view taken on 30 the line 2—2 of Fig. 1.

Fig. 3 is an enlarged end elevational view of the guide taken on the line 3—3 of Fig. 1.

Referring now to the drawings the invention will be described in detail.

35 In Fig. 1 a portion of a web of material W such as cloth or the like is shown and to facilitate a clear understanding of the invention it will be assumed that the web is traveling in the direction indicated by the arrow for 40 delivery into a machine of some sort or is being wound up on a reel. Naturally the side edges of the web shift laterally in one direction or the other while it is thus traveling which is objectionable for many reasons. To 45 overcome this shifting movement according to the invention I provide a guiding apparatus represented generally by G at opposite side edges of the web. The guiders at opposite sides of the web are alike and only one 50 is shown in the drawing.

The guider consists in general of a pair of coating rolls 2 and 4 for engaging opposite sides of the web at its side edges, the latter of which is movable towards and away from the former so as to engage or release the web. 55 The roll 2 is mounted for free rotation on a plate 6 while the roll 4 is rotatably mounted in an arm 10 pivoted for swinging movements on said plate 6. This plate 6 is adapted to support the mechanism and may itself be supported from a floor by a standard 12 fixed to a boss 14 at the rear side thereof. Preferably the plate will be disposed so as to position the rolls angularly with respect to the edge of the web as shown so that as the rolls 60 bear on opposite sides of the web the web will tend to move upwardly with respect thereto or shift laterally and in this way be moved in one direction by the rolls of the guide shown or released thereby and moved in the 65 opposite direction by a similar guide mechanism at the opposite side of the web.

The roll 4 is moved towards the roll 2 by means of the following. A solenoid S of ordinary construction is mounted on the plate 70 75 6 and has as usual a plunger 16 reciprocable therein, the lower end of which receives the end of a lever 18 fixed to one end of a rock shaft 20 in the plate 6. A lever 22 is fixed to the other end of the rock shaft 20 and has its 80 end connected by a link 24 to the lower end of the lever 10. In the position shown the plunger 16 is being acted upon by the solenoid and the parts are arranged so that in this position the roll 4 engages the web between it 85 and the roll 2.

As before stated the solenoid is of common form and as usual may be energized for its pulling action by delivering an electrical current thereto. As the flow of current is cut off the plunger is free to drop so that the roll 4 may fall away from the roll 2.

A feeler F pivoted at 24 to the plate for 90 swinging movements in a plane transverse to the direction of movement of the web is arranged to be engaged by the edge of the web as shown in Fig. 2. An extension 26 provided on the feeler has fixed thereto contact members 28 which are adapted to engage other contacts 30. The contacts 28 are suit- 95 100

ably insulated from the extension 26 by a pad 32 while the contacts 30 are similarly fixed on an insulated pad 34 carried by a bracket 36 fixed on the plate 6. These contacts will be suitably connected by wires to the solenoid and an electrical current supply so that when engaged the solenoid will be energized.

In operation with the rolls in the angular position described the feeler F will tend to swing away from the plate so that it lies against the edge of the web. The parts will be so adjusted that when the edge of the web runs to the right of a predetermined location the feeler will be allowed to swing to engage the contacts 28 and 30. With these closed the solenoid is energized and the roll 4 moved towards the roll 2 so that the web is engaged therebetween. By being engaged between the rolls there is as before stated a tendency for the web to move upwardly of the rolls and laterally of its direction of travel and according to the adjustment of the parts the feeler which is moved by the web will disengage the contacts so that the solenoid is no longer energized in which case the roll 4 falls away from the roll 2.

In this way as the edge of the web moves to the right the feeler moves to energize the solenoid so that the rolls engage the web which then moves relative to the rolls to the left until the feeler breaks the electrical connection. By locating guiding mechanism on opposite sides of the web and by arranging the parts for the purpose the guiders may function to engage and move the web laterally in one direction or the other whenever it runs out of alignment.

In lieu of the solenoid shown it may be desired to provide a magnet or magnets or the like for moving the roll and lever towards the non-movable roll, the current supply to said magnet being controlled by a suitable switching device under the influence of the feeler.

Various changes and modifications may be made in the form of the device without departing from the spirit and scope of the invention and I prefer therefore to be limited by the appended claims rather than by the foregoing description.

What I claim is:

1. Guiding apparatus for a traveling web of material, a support, a roll pivoted thereon side of a web rotatable thereon, a roll lever pivoted on said support having a roll rotatable in the free end thereof for engaging the other side of a web and pressing it against the first-named roll, an oscillatable shaft in said support, an operating lever on said shaft connected to said roll lever, an electrically operated device connected to said shaft for operating the same, a lever pivoted on support for engaging the side edge of a web and being movable thereby and switch elements car-

ried by said support and lever engaged and disengaged by relative movements thereof.

2. Guiding apparatus for a traveling web of material, a support, a roll pivoted thereon for bearing an outer face of a web, a roll lever pivoted on said support carrying a rotatable roll for bearing on an inner face of a web and pressing said web against said first-named roll, a shaft oscillatable in said support, an electrical device having a reciprocable member, a lever on said shaft connected to said member, a second lever on said shaft connected to said roll lever, a feeler pivoted on said support on an axis opposed to those of said rolls having a part for engaging the side edge of a web, and switch mechanism carried by said feeler and support which opened and closed as the feeler swings back and forth.
